UNITED STATES PATENT OFFICE

WILLIAM BROWN, OF GLASGOW, SCOTLAND

SMOKE-CONSUMING DEVICE

Application filed May 3, 1926, Serial No. 106,506, and in Great Britain February 26, 1926.

This invention relates to a method of consuming smoke and to apparatus for carrying out this method; the method and apparatus not only enabling the smoke to be consumed but also enabling the waste products of combustion to be utilized.

After considerable experimental work I have discovered that smoke can be consumed by a method in which a pipe or passage having means for providing a flame to project thereinto and for providing a stream of gas which will support combustion are used to receive the smoke or products of combustion from the furnace (hereinafter referred to merely as smoke) and to consume the smoke prior to discharge.

Apparatus for effecting this comprises a hollow member forming a passage having an inlet for the smoke at one end thereof and having an outlet at the other end thereof, means for producing a flame to project into the said hollow member and means for supplying a gas which will support combustion within the hollow member.

25 The hollow member forming the passage for the smoke may extend through the water space in the case of a boiler or it may be otherwise arranged that the heat from the combustion of the smoke is utilized.

30 This invention is particularly applicable to boilers for generating steam and in its application to such the hollow member extends from the smoke box through the water space and has an inlet for smoke at the smoke box end and an outlet at the other end while the means for projecting the flame and for supplying a stream of gas which will support combustion to the hollow member are provided as before and the whole is so arranged 35 that the smoke is consumed and the heat generated thereby is utilized prior to its discharge from the hollow member.

It is important that the stream of gas to support combustion in the hollow member 45 will take up and propagate the flame substantially throughout the length and breadth of the hollow member.

In order that the nature of the invention 50 may be clearly understood the application of this apparatus to boilers for generating steam

will now be described, simply by way of example, with reference to the accompanying drawings, wherein:—

Fig. 1 is a sectional elevation of a boiler arranged for consuming the smoke and utilizing the heat generated thereby.

Figs. 2 and 3 are side sectional elevation and end elevation respectively of an alternative form of such apparatus. Like reference numerals indicate similar parts throughout the drawings.

In the preferred construction the boiler is provided with a hollow member in the form of a pipe 1 (hereinafter termed the consuming pipe) which is disposed centrally within the boiler and extends longitudinally thereof from the smoke box 2 through the water space 3 and projects outwardly of the boiler at the opposite end to the smoke box. The end 1^a of this consuming pipe which is within the smoke box is open and the opposite end which projects from the boiler is provided with a discharge passage or pipe 1^b which in the case of stationary boilers may lead to the chimney.

A pipe junction 4 having a gas burner 5 and also having a nozzle 6 arranged as shown, with an open 4^a for lighting the burner is provided in a position centrally of the smoke box end of the consuming pipe. The gas burner is preferably connected with a supply of coal gas and the nozzle is connected by the pipe 7 to a blower 8 adapted to supply air under pressure; the arrangement being such that the air tends to project a flame from the burner within the consuming pipe. The blower also serves to supply a forced draught to the fire, a pipe 10 (hereinafter called the forced draught pipe) being provided extending into the ash box of the furnace in a position beneath the fire bars. This pipe may be provided with a separate angle piece 11 on its end adapted to direct the forced draught upwardly and in this case it is advisable to arrange that this angle piece 11 is rotatable and has means such as the hand wheel 12 disposed exteriorly of the ash box for rotating it so as to enable any ash which may fall therein and tend to choke the pipe to be removed.

A valve such as that marked 13 is also provided for controlling the flow of air

through the forced draught pipe. By controlling the flow of air through the forced draught pipe not only is the amount of smoke produced by the fire varied but also the amount of air supplied to the nozzle 6 is varied; so that by operation of the valve 13 the relative amount of smoke and gas supplied to the hollow member is regulated, thus ensuring complete combustion of smoke.

10 The boiler is heated by the furnace 14 which is fed with fuel through the opening 15 normally closed by a door 16. The smoke passes upwardly as indicated by the arrows through the flue 17 into the smoke box 2 and from there passes through the open end 1^a of the consuming pipe 1 in which it is burnt up. Any waste gases escape by the discharge pipe 1^b.

15 It will be seen that the smoke is burnt up by the combined action of the air and flame which is propagated throughout substantially the whole length and breadth of the consuming pipe and it is found that with proper regulation of the supplies of air and gas and 20 of the smoke that it is possible entirely to consume the smoke. The flame must act on all the smoke passing through the pipe and it must act upon it for a period sufficient to ensure its complete combustion.

25 As an alternative to the above the smoke may be consumed by arranging that part of the smoke is passed to the fire in the furnace and part to the consuming pipe.

30 A boiler having apparatus designed to effect this is shown in Figs. 2 and 3 in which the consuming pipe 20 is arranged as before except that the position of the outlet and the pipe junction for supplying gas and air are reversed, the pipe junction 21 for supplying 35 coal gas and air (which is similar in construction to that shown in Fig. 1) being in this case arranged at the end which projects from the boiler and the outlet 20^b being provided at the smoke box end. In this case also 40 a transfer pipe 22 is provided extending between the smoke box 23 and the forced draught pipe 10, this serving to convey the smoke from the smoke box down through the forced draught pipe and to direct it upwardly 45 beneath the furnace. A further transfer pipe 24 is provided having an inlet 25 immediately above the outlet of the forced draught pipe in the ash box, said transfer pipe extending upwardly and having an outlet 26 communicating 50 with the consuming pipe at or near the end which is provided with the gas and air fitting. This transfer pipe from the ash box is preferably provided with a control valve 27 and is arranged that part of the 55 smoke together with air from the blower is passed upwardly through the fire and a part is passed through this transfer pipe into the consuming pipe; the amount passing through the transfer pipe and consequently the amount 60 passing through the fire being controlled by 65

the valve in the transfer passage. Thus by operating the valve 27 the relative amount of smoke and air supplied to the pipe 20 can be regulated as in the construction described with reference to Fig. 1. In this case the smoke will be consumed in the pipe as before.

70 It will be understood that in both cases the ash box and respective passages for the smoke or air must be substantially air tight.

75 Moreover the consuming pipe projects through the water space of the boiler so that the heat caused by burning the smoke is utilized to heat the water and thereby increase the efficiency of the boiler.

80 In the exemplary construction described and illustrated coal gas is used to produce the flame, but it will be understood that any other means may be provided for attaining this end, for instance, oil fuel, particularly where oil is used as fuel for the furnace, and also an electric arc similar to that in the well known electric arc metallurgical furnaces. Further, although air (being the cheapest and most convenient gas for supporting the combustion) is preferably used, 85 any other gas known to support combustion may be employed within the scope of this invention.

90 Having now fully described my invention what I claim and desire to secure by Letters Patent is:—

95 1. Apparatus for consuming smoke from furnaces, comprising in combination, a furnace, a smoke box communicating with said furnace, a hollow member having an inlet 100 communicating with said smoke box and an outlet externally of said smoke box, a burner adjacent the inlet end of said hollow member and adapted to produce a flame, means for providing a supply of combustion-supporting gas under pressure, a conduit for said gas leading from said means to a point beneath the furnace for supplying a forced draught therefor, a valve for said conduit, a second conduit branching from said first conduit and positioned intermediate said means and said valve, said second conduit leading to a nozzle adjacent the burner, the gas flow from the nozzle being adapted to direct the burner 105 flame into the hollow member, and the arrangement of the aforesaid first and second conduits and the valve enabling the relative amount of smoke and gas supplied to the hollow member to be regulated.

110 2. Apparatus for consuming smoke from furnaces, comprising in combination, a furnace, a smoke box communicating with said furnace, an air-tight ash box for said furnace, a hollow member forming an outlet for the smoke from said smoke box having an inlet 115 end extending into the smoke box and an outlet end exterior to said smoke box, a burner adjacent the inlet end of said hollow member and disposed at an angle thereto adapted to produce a flame, means for providing a sup- 120

ply of combustion-supporting gas under pressure, a conduit for said gas leading from said means to said ash box for supplying a forced draught for the furnace, a valve for said conduit, a second conduit branching from said first conduit and positioned intermediate said means and said valve, said second conduit leading to a nozzle adjacent the burner, the gas flow from the nozzle being adapted 10 to direct the burner flame into the hollow member, and the arrangement of the aforesaid first and second conduits and the valve enabling the relative amounts of smoke and gas supplied to the hollow member to be 15 regulated.

In testimony whereof I affix my signature.
WILLIAM BROWN.
